UNITED STATES PATENT OFFICE.

ROBERT R. KINTZ, OF MERIDEN, CONNECTICUT, ASSIGNOR TO INTERNATIONAL SILVER CO., OF MERIDEN, CONNECTICUT, A CORPORATION OF NEW JERSEY.

DESIGN FOR A MOUNT FOR DISHES.

SPECIFICATION forming part of Design No. 36,492, dated August 11, 1903.

Application filed July 20, 1903. Serial No. 166,414. Term of patent 8½ years.

To all whom it may concern:

Be it known that I, ROBERT R. KINTZ, of Meriden, in the county of New Haven and State of Connecticut, have invented a new, original, and ornamental Design for a Mount for Dishes; and I do hereby declare the accompanying drawing to be a full, clear, and exact illustration of the same, and which said drawing constitutes part of this specification and represents a face or plan view of a mount for dishes embodying my design.

I claim—

The ornamental design for a mount for dishes as shown.

In testimony whereof I have signed this specification in the presence of two subscribing witnesses.

ROBERT R. KINTZ.
